UNITED STATES PATENT OFFICE.

THOMAS O. MATTHEWS, OF AVALON BOROUGH, PENNSYLVANIA, ASSIGNOR TO JAS. H. MATTHEWS & CO., OF PITTSBURG, PENNSYLVANIA, A CORPORATION OF PENNSYLVANIA.

CAN-MARKING DEVICE.

No. 926,271.

Specification of Letters Patent.

Patented June 29, 1909.

Application filed June 4, 1908. Serial No. 436,554.

To all whom it may concern:

Be it known that I, THOMAS O. MATTHEWS, a citizen of the United States, and residing in the borough of Avalon, in the county of 5 Allegheny and State of Pennsylvania, have invented or discovered new and useful Improvements in Can-Marking Devices, of which the following is a specification.

My invention consists in certain new and 10 useful improvements in mechanism for stamping or impressing letters, numbers or other characters or marks on sheet metal articles such as caps or covers for cans, bottles and other receptacles. It may be applied 15 to any type of stamping or impression press or similar device. The article to be marked is engaged by coacting male and female type containing the desired characters which are 20 adjustably and removably mounted and arranged in holders which are in turn securable to the press. The female type are preferably mounted on a removable form which 25 is secured in the upper holder attached to the plunger of the press, while the male type are mounted in a holder which is secured to the bed plate of the press. The form in which the female type are mounted is shown 30 provided with a slot or slots, of which there may be any desired number as dictated by the number of lines of characters desired, 35 through which the type extend downwardly, being prevented from falling through the slot by their shoulders. The male type are mounted in a slot or slots in the lower holder 40 and are prevented from dropping out of place by means of the bottom of the slot, which bottom may be of hardened steel to 45 resist the impact. It is evident that in the use of my invention any desired number of lines of characters may be used and any number of characters desired in each line, dependent on the area of the holders and the length and number of the slots. The type 50 are preferably marked on their reverse ends with the character which is provided on the impression ends and also with a mark under the same to indicate the direction in which they are to be turned to be properly set.

In the accompanying drawings, Figure 1 55 is a perspective of a stamping press fitted with my invention; Fig. 2 is a front view of the upper and lower holders on an enlarged scale; Fig. 3 a side elevation of the same showing two rows of type; Fig. 4 is an inverted plan view of the upper holder block

and form; Fig. 5 is a perspective of a male type and Fig. 6 shows a similar view of a female type with a bottom plan view attached.

The following is a detailed description of the drawings.

1 is a stamping press of well known design. My invention may be applied to any form of press but the one shown is well known and illustrates the principles of my invention in operation.

2 is the plunger and 3 the plunger socket.

4 is the bed plate.

5 is the upper holder, which to fit the plunger socket 3 is in this case provided with a rigid spindle 6 adapted to engage said socket and be secured therein by means of set screw 7. The holder 5 is provided with a recess 8 across its lower face from side to side which recess is provided with beveled side walls 9—9 which are engaged by the beveled sides of the form 10 which is slid into said recess and retained from dropping out by said beveled walls.

11 is a second recess cut in the floor of recess 8 and also extending from side to side of holder 5, into which recess extend the shanks of the female type mounted in form 10, said type bearing against the bottom of said recess when an impression is being made.

12 is a back plate attached to holder 5 and extending across the rear of recess 8 to limit the movement of form 10. The form 10 is provided with knob 13 for its manipulation. 14 is a spring pin mounted in holder 5 and adapted to enter a hole in the wall of form 10 and hold the same rigidly in place in said recess 8 when the press is prepared for operation. By drawing out said pin against its coiled spring, the form may be readily slipped from the holder when desired. Said form 10 is provided with one or more slots 15—15 in which are mounted or set the female type 16—16, said type being provided with shoulders 17—17 to prevent their dropping down through said slots. I have shown two type slots in Fig. 4 but it will be understood that any desired number of slots may be provided and the same may be of any desired length, controlled of course by the area of the form used.

The type which are preferably mounted in the form 10 are the female type shown in Fig. 6 and blocks or spacers are used to fill in the slots where sufficient type to fill the same are not used.

The lower holder is composed of a bottom

plate 18 which may be attached to the platform 4 of the press with set screws or other convenient means, and block 19 which is provided with one or more type slots 20—20, 5 which correspond in number to the slots 15—15 in form 10. In said slots 20—20 are mounted the male type 21—21 which may be secured therein by means of blocks or spacers or in any other convenient manner.

10 The reverse ends of type 16—16 are marked with the letter or number which the type will stamp, and also with a small dot or mark, 22, to indicate the proper position in which the type should be placed to print uniformly, 15 the type being set upside down in the form 10.

The operation of my invention is as follows:—The form 10 is removed from recess 8 in the holder 9 and the proper female type 16—16 inserted downwardly therein until 20 suspended from their shoulders 17—17. Sufficient blanks are also introduced in a similar manner to block the type rigidly in place. The form is then slipped into recess 8 and locked therein by means of spring pin 25 14, the tops of the type bearing against the material of the block 5. The proper male type, 21—21, to correspond to the said female type both in character and arrangement, are next introduced into slots 20—20 30 of the lower holder and blocked therein. Thus under each female type there is located a coacting male type bearing the same character. The upper holder is now placed in the press by slipping its spindle 6 into socket 35 3 and securing the same therein by means of set screw 7. The lower holder is now placed on platform 4 and secured thereto as aforesaid. The cap or other article to be marked is now rested on the top of male type 21—21 40 and the press is operated depressing plunger 2 thus forcing the female type 16—16 down on the article to be marked. The type 21—21, resisting the depression of the article, force the material thereof into the female 45 type 16—16, thus forming raised numbers, letters or other characters in the material of the article.

If desired the position of the male and female type may be reversed, but I prefer the 50 arrangement shown.

The advantages of my invention over the present methods of impressing or marking

articles of such character are self-evident. The data which is placed on caps, covers or lids of receptacles is not constant, but, as in the case of food products for instance, must frequently be changed to indicate date of packing, character of goods &c. If a separate stamp were required for each change, the expense would be prohibitive could the marking be advantageously omitted. I provide means whereby the data can be set up from individual type in a few moments by the most unskilled labor and the exact data desired stamped on the articles in one impression. I thus do away with a multiplicity of stamps, duplicates of each other in many instances except for a single character. In the use of such stamps great care must be observed in selecting the proper stamp in each 70 case from a quantity of similar stamps. The arrangement and construction of parts shown by me is both simple and novel.

I have shown my invention applied to a well known type of press but its applicability 75 to any design of press is evident. The durability of my invention is also of great advantage. When type become so worn as not to properly coact to give a clear impression, new type may be substituted at trifling expense and the equipment is restored to its original condition. The holders and form are practically indestructible.

What I desire to claim is:—

In a can marking device, the combination 85 of a press having a stationary bed and a plunger, a slotted block secured to said bed, type members set in the slots of said block, a second block secured to said plunger provided with a recess on its lower face, a slotted type form occupying a portion of said recess and shouldered type members bearing against the top of said recess and depending through the slots of said form, said first and last mentioned type members co-acting to 90 mark the can, substantially as and for the purpose set forth.

Signed at Pittsburg, Penna., this 1st day of June, 1908.

THOMAS O. MATTHEWS.
